CLAIM

I claim the ornamental design for a machine for manufacturing cigarette, as shown and described.

DESCRIPTION

FIG. 1 is a front, top, right side perspective view of a machine for manufacturing cigarette showing my new design;

FIG. 2 is a rear, top, left side perspective view thereof;

FIG. 3 is a rear, bottom, left side perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines in the drawings depict portions of the machine for manufacturing cigarette that form no part of the claimed design. The dash-dot broken lines in the drawings define the boundary of the claimed design; the claimed design extends to the boundary but does not include the boundary.
